UNITED STATES PATENT OFFICE

2,584,609

AWNNG

Gayle G. Owen, Minden, La.

Application January 29, 1948, Serial No. 5,029

3 Claims. (Cl. 20—57.5)

1

This invention relates to new and useful improvements in awnings and the primary object of the present invention is to provide an awning so designed as to protect a window against rain, snow or the like and to prevent rain from contacting and rusting window screens.

Another important object of the present invention is to provide a rigid protective awning for windows including novel and improved light admitting openings that are so arranged and shielded as to prevent rain, snow or the like from passing therethrough.

A further object of the present invention is to provide a collapsible or pre-fabricated awning construction that is extremely small and compact in structure facilitating the convenient handling of the same during transporting, assembling or disassembling thereof.

A still further aim of the present invention is to provide an awning that is simple and practical in construction, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of the present awning applied to an outside wall adjacent a window structure;

Figure 2 is a front elevational view of the present awning structure;

Figure 3 is a side elevational view of Figure 1;

Figure 4 is a longitudinal vertical sectional view taken substantially on the plane of section line 4—4 of Figure 1;

Figure 5 is a group perspective view of the frame used in conjunction with the present invention; and,

Figure 6 is an enlarged vertical sectional view taken substantially on the plane of section line 6—6 of Figure 2.

Referring now to the drawings in detail, wherein for the purpose of illustration, there is disclosed a preferred embodiment of the present invention, the numeral 10 represents the supporting frame of the present invention generally, comprising a pair of spaced parallel substantially L-shaped side members having vertical leg portions 12 and horizontal leg portions 14. The vertical leg portions 12 are provided with a plurality

2

of apertures 16 that facilitates the removable securing of said leg portions by suitable fasteners to the side boards 18 of a window opening or casing.

5 Rigidly secured to the outer free ends 20 of the lower or horizontal leg portions 14, are the angulated or downwardly turned lower terminals 22 of a pair of forwardly and downwardly inclined support arms 24, the upper terminals 26 of which are fixedly secured to the upper terminals 28 of the vertical leg portions 12.

Connecting the outer ends 20 of the horizontal leg portions 14, is a rigid cross member or bar 30 that retains the leg portions 12 and 14 of the side members spaced relative to each other, and the inclined support arms 24 substantially parallel and coplanar.

The numeral 36 represents generally a pair of stepped side panels, comprising a plurality of adjacent, spaced, outwardly and downwardly inclined integral slats 38 that are preferably formed from a single sheet of bendable metal and which are spaced parallel to each other with their outer edges 40 being coplanar, and their inner edges 42 also being coplanar and spaced parallel to the outer edges 40. The inner edges 42 and outer edges 40 of the adjacent slats 38 are connected by downwardly and inwardly inclined spacer strips 44 that are integrally formed with the said slats. The spacer strips 44 are provided with longitudinally spaced, inwardly struck tongues or guards 46 that form shields for the light admitting openings 48 in the strips. The lower strips 50 carried by the lower of the slats, referred to by the numeral 52, are provided with integral attaching slats 54 which are rigidly secured to the horizontal legs 14, and the side panels are further secured by rivets or the like 56 to the vertical leg portions 12. In such a secured position, the outer edges 40 and the inner edges 42 terminate in planes that are spaced parallel to the leg portion 12, the horizontal leg portions 14, and the support arms 24.

The numeral 58 represents generally the forward panel of the present awning structure comprising a plurality of adjacent, spaced parallel integral slats 60 which are formed or crimped from a single sheet of bendable metal. The adjacent inner and outer edges 62 and 64 of the slats 60 are connected by inclined spacer strips 66 having longitudinally spaced, inwardly struck guard tongues or shields 68 to provide light admitting openings 70. These slats 60 are secured by rivets or the like 72 to the inclined support arms 24. Projecting outwardly from the lower

strip 74 of the lower slats 76, is an attaching strip or flange 78 that is rigidly secured to the cross bar 30, and projecting outwardly from the upper slat 77 is a flange 79 that is secured by suitable fasteners in a position above the window casing.

It should be noted, that the outer faces of the slats 38 and 60 are inclined outwardly and downwardly relative to the vertical leg portions 12 and support arms 24 respectively, and that the strips 66 are spaced parallel to each other and to the vertical leg portions 12, so that the same will be shielded by the slats 60. The guards or shields 46 and 48 are bendable at a selected angle to prevent rain, snow or the like from entering the openings 48 and 70 to contact the window panes or screens protected by the present awning.

The side edges 80 of the slats 60 are coplanar with and are suitably secured to the inclined, adjacent side edges 82 of the slats 52, also, the side edges 84 of the strips 66 are coplanar with and are suitably secured to the inclined adjacent, side edges 86 of the strips 44.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. An awning comprising a supporting frame, a pair of spaced side panels fixedly carried by said frame, a forward panel fixedly carried by said frame, each of said panels having a plurality of horizontally extending, parallel outwardly and downwardly inclined slats, substantially upright strips connecting adjacent horizontal edges of said slats and light admitting openings in said strips, said forward panel hav-

ing its slats disposed in vertically spaced relation and its strips being disposed in parallel substantially upright planes, said strips having integral portions above their lower edges cut away to provide said openings and integral shields extending from said strips at one of the edges of each of said openings in parallel relation to the adjacent slat.

2. A ventilated metal awning including an inclined roof panel having a plurality of vertically spaced, longitudinally extending slats in parallel planes, the adjacent longitudinal edges of juxtaposed slats being joined by substantially upright strips, said strips having openings above their lower edges, integral portions of said strips extending from one of the edges of each of the openings in parallel relation to the adjacent slat to form light admitting opening and rain deflectors therefor.

3. A ventilated awning comprising an awning supporting frame for mounting an awning upon a supporting surface, a panel carried by said frame and fixedly secured thereto, said panel having a plurality of horizontally elongated and extending, parallel outwardly and downwardly inclined portions, substantially upright strips engaging adjacent horizontal edges of adjacent portions, said strips having light and ventilating openings therein, said strips having the extensions on one of the edges of each of said openings, said extensions extending in parallel relation to an adjacent portion.

GAYLE G. OWEN.
